his ATTORNEY

UNITED STATES PATENT OFFICE

CHARLES P. SCHLEGEL, OF ROCHESTER, NEW YORK, ASSIGNOR TO SCHLEGEL MFG. COMPANY, OF ROCHESTER, NEW YORK, A CORPORATION OF NEW YORK

CABLE WITH ATTACHED POMPONS

Application filed November 7, 1929. Serial No. 405,523.

The present invention relates to cables with attached pompons, and an object of the invention is to provide a novel clamp to which the pompon may be secured. Another object 5 of the invention is to provide a novel means of securing the pompon securing wire to the clamp. Still another object of the invention is to provide a novel manner of holding a ferrule about the clamp adjacent the pompon. 10 Another and still further object is to provide a novel means of holding the pompon in centered position.

To these and other ends, the invention consists of certain parts and combinations of 15 parts all of which will be hereinafter described, the novel features being pointed out in the appended claims.

In the drawings:

Fig. 1 is a side view of a device embodying 20 the present invention with the ferrule in section and part of the pompon broken away;

Fig. 2 is a view at right angles to that shown in Fig. 1 with the ferrule in section and part of the pompon broken away;

Fig. 3 is an enlarged view of the clamp in 25 vertical section and the pompon securing wire in side elevation;

Fig. 4 is a perspective view of the clamp;

Fig. 5 is a top view of the clamp and the 30 pompon securing wire; and

Fig. 6 is a detail view showing the manner in which a stiffening spring is secured by the clamp.

Referring more particularly to the illustrated embodiment of the invention 1 indicates the cable which, in this instance, acts as a grip strap in automobiles. At the end of this cable is arranged the pompon 2, while about the cable abutting the pompon is a ferrule 3.

One end of the cable has secured thereto a clamp comprising, in this instance, two arms 4 and 5, engaging opposite sides of the cable and connected beyond the end of the cable by 45 a portion 6 which forms a loop or eye. The upper or free ends of the arms are provided with tongues or pointed projections 7 which are forced into the cable. Between these projections and connection 6 the arms are tied together. This is secured, in this instance, by

providing one of the arms with tongues or projections 8 on opposite sides, and the other arm with an opening 9. The projections 8 are passed over the arm 5 and bent into the opening 9, thus providing an interlocking 55 connection. The projections are forced at their ends into the cable and serve as additional anchorage for the clamp.

The pompon 2 is formed about the ring portion 10 of a wire which has its ends passed through the eye or loop formed by the bend 6 after which the ends are carried upwardly on the outer sides of the clamp to provide centering portions 11 for the ferrule 3 on opposite sides of the clamp. The wire is 60 then bent laterally at 12 and again downwardly at 13 to provide two more centering portions for the ferrule between the centering portions 11 so that the ferrule is supported at four substantially equidistant 65 spaced points. The ends of both of the portions 13 are pointed and extended outwardly to produce hooks 14 which provide securing means for holding the ferrule.

If desired, a coiled spring 15 may extend 70 longitudinally of the cable to hold the latter in a normally straight condition, and the lower end of the spring may extend into the portion of the cable held by the clamp so as to secure the lower end of the spring 75 against movement, as shown in Fig. 6.

From the foregoing it will be seen that a novel clamp has been provided for securing a pompon to a cable. The pompon securing wire also serves as a centering means for 80 the ferrule and a securing means for the ferrule and is connected to the clamp in such a manner that disconnection of the pompon is not liable to take place.

What I claim as my invention and desire 85 to secure by Letters Patent is:

1. A grip strap for automobiles comprising a cable, a pompon, a clamp having arms engaging opposite sides of one end of the cable and having a loop connecting said arms 90 beyond said cable end, a pompon holding device passed through said loop, and interlocking means formed integrally on said arms for tying the same together in clamping engagement with said cable end.

2. The combination with a cable of a sheet metal clamp having arms formed to embrace opposite sides of one end of said cable, a connecting portion between said arms beyond said cable end, said arms being integrally provided with one or more projecting portions for securing engagement with said cable and with cooperating portions for tying said arms together to clamp said cable therebetween, a pompon secured to said connecting portion, and a ferrule positioned about said clamp. 70
3. The combination with a cable, of a clamp for the end of the cable comprising two arms engaging opposite sides of the cable, a connecting portion between the arms arranged at the end of the cable, and two projections carried by opposite sides of one of the arms and interlocking with the other arm. 75
4. The combination with a cable, of a clamp for the end of the cable comprising two arms engaging opposite sides of the cable, a connecting portion between the arms arranged at the end of the cable, and interlocking means carried by the two arms for tying the two arms together independently of said connection. 80
5. The combination with a cable, of a clamp for the end of the cable comprising two arms engaging opposite sides of the cable, a connecting portion between the arms arranged at the end of the cable, one of said arms having an opening, two projections carried by the other arm and extending into the opening to tie the arms together. 85
6. The combination with a cable, of a clamp for the end of the cable comprising two arms engaging opposite sides of the cable, a connecting portion between the arms arranged at the end of the cable, one of said arms having an opening, two projections carried by the other arm and extending into the opening to tie the arms together, the ends of said projections passing into the cable to anchor the clamp to the cable. 90
7. The combination with a cable, of a clamp comprising arms engaging opposite sides of one end of said cable, means connecting said arms beyond said cable end, projecting portions on the ends of said arms having securing engagement with said cable, and interlocking means on said arms between said connecting means and said projecting portions for tying said arms together independently of said connecting means. 95
8. The combination with a cable, a clamp for an end of the cable, a pompon secured to said clamp beyond the end of the cable, a ferrule surrounding the clamp, and a ferrule securing means supported by said clamp. 100
9. The combination with a cable, of a clamp secured to the cable, a pompon, a ferrule surrounding the clamp, and a pompon securing wire having means thereon for securing the ferrule. 105
10. The combination with a cable, of a clamp secured to the cable, a pompon arranged beyond the cable, a ferrule surrounding the clamp, and a pompon securing wire anchored in the clamp and having end portions holding the ferrule in position. 110
11. The combination with a cable, of a clamp secured to the cable and provided with a loop beyond the end of the cable, a pompon, and a pompon securing wire passed through said loop. 115
12. The combination with a cable, of a clamp secured to the cable and provided with a loop beyond the end of the cable, a pompon, and a pompon securing wire passed through said loop, and having end portions provided with hooks, and a ferrule surrounding the clamp and held by the hooks. 120
13. The combination with a cable, and a clamp secured to the cable, of a pompon secured to the clamp, a ferrule surrounding the clamp, and a centering means for the ferrule comprising four longitudinally extending spaced portions about the clamp. 125
14. The combination with a cable, and a clamp secured to the cable, of a pompon secured to the clamp, a ferrule surrounding the clamp, and a centering means for the ferrule comprising four longitudinally extending spaced portions about the clamp, at least one of which has a hook to hold the ferrule in place. 130
15. The combination with a cable, of a clamp having arms engaging opposite sides of one end of said cable, a connecting portion between said arms beyond said cable end, and interlocking means carried by said arms for tying said arms together, said interlocking means being arranged to also engage said cable end for additionally securing said clamp thereto. 135
16. A grip strap for automobiles comprising a cable, a pompon, a clamp secured to one end of said cable, a ferrule about said clamp and cable, and means for securing said pompon to said clamp having one or more portions extending along said cable end for centering said ferrule. 140
